CLAIM

The ornamental design for a bathroom mirrored cabinet and light fixture assembly, as shown and described.

DESCRIPTION

FIG. 1 is a front elevational view of a bathroom mirrored cabinet and light fixture assembly showing my new design;

FIG. 2 is a right side elevational view thereof, the left side being a mirror image of that shown; and, FIG. 3 is a rear elevational view thereof.

FIG. 1
